UNITED STATES PATENT OFFICE.

EDSON O. SESSIONS, OF CHICAGO, ILLINOIS, ASSIGNOR TO ALBERT C. BELL, TRUSTEE,
OF CHICAGO, ILLINOIS.

INSULATOR SUPPORT.

Application filed June 13, 1919. Serial No. 304,023.

To all whom it may concern:

Be it known that I, EDSON O. SESSIONS, a citizen of the United States, residing at Chicago, in the county of Cook and State of Illinois, have invented a certain new and useful Improvement in Insulator Supports, of which the following is a specification.

My invention relates to an improved form of insulator support by which an insulator 10 may be mounted and clamped in a desired position to support an electrical conductor, the clamping portion of the support being readily adjustable relatively to and removable from its supporting base thus permitting 15 the bases of such supports to be installed before the clamping members and insulators are put in place.

My invention will best be understood by reference to the accompanying drawings 20 showing a preferred embodiment thereof in which—

Fig. 1 shows a support in end elevation clamping an insulator in its supporting position, a part of the insulator and base being 25 cut away to more clearly show the construction of the support.

Fig. 2 is a side elevation of the parts shown in Fig. 1.

Fig. 3 is a bottom view of the base and 30 adjacent ends of the clamping members shown in Fig. 1.

Fig. 4 shows in a view similar to Fig. 1, one of the clamping members before being used,

Fig. 5 shows in a view similar to Fig. 1 a modified construction of base for engaging 35 a cylindrical support instead of a flange base as shown in Fig. 1, the clamping members being of the same construction in this case as shown in Fig. 1, and

Fig. 6 shows in a view similar to Fig. 2 the parts shown in Fig. 5.

Similar numerals refer to similar parts throughout the several views.

As shown in Figs. 1, 2 and 3, my improved support consists of a flange base 10 having a central circular aperture 11 which is undercut at its inner end as indicated at 12 to a larger diameter than the diameter of the remaining portion of said aperture. Holes 13 are formed through the projecting flange portions of the base to receive fastening devices not shown by which the base and support may be secured in desired position in use. Two clamping members 14 provided

with projecting legs 15 extending into the aperture 11 are provided, these legs ending in projecting toes or flanges 16 entering the larger portion 12 of the aperture through the base so that the engagement between said toes and the shoulder in said aperture prevents the withdrawal of said members from the base when in use. The members 14 project outwardly from the base in semi-circular conformation to surround a cylindrical insulator 17 to be held in place by the support. A clamping bolt 18 extends through the outer ends of the members 14 to hold them in clamping relation relatively to the said insulator. The members 14 have formed thereon between the insulator and the base and preferably adjacent the insulator, bosses 19 so conformed that the action of the bolt 18 in moving the members to their clamping position brings the bosses 19 firmly together 75 and at the same time moves the toes 16 firmly against the portion 12 of the aperture through the base before said members engage the outer surface of the insulator. As a result the clamping members are rigidly 80 secured to the base before any clamping action is exerted upon the insulator and increased clamping action exerted by the bolt 18 serves to spring the members 14 sufficiently to permit bringing them into engagement 85 with the outer surface of the insulator 17 with any desired degree of pressure. To facilitate the operation described each of the members 14 is formed as shown in Fig. 4 with an inner surface 20 of slightly greater 90 radius than the radius of the insulator to be supported by the clamping members, the projecting end 21 of the clamping member being displaced sufficiently back of a central plane through the face of the boss 19 so that when said member is forced into a clamping position as shown in Fig. 1 the projecting end 21 will not engage the corresponding end of the other member. For the best results, the conformation of the inner surfaces of the members 14 should be such, taking into account the metal distribution in said members, that the stress in said members is distributed uniformly or substantially so throughout their length along the portions of said members 14 adjacent the insulator to be clamped thereby, or in other words there shall be a uniform and slight distortion of the members 14 by the clamping action 105 throughout said portions of the said mem- 110

bers; in some cases the curvature of the inner surfaces of the members 14 may have a single radius of curvature somewhat larger than the radius of the insulator to be clamped by the members and in other cases the said inner curvature may result from the use of an increasing radius of curvature from the bosses 19 along the clamping surfaces of said members; it will be understood 10 however that my invention includes any curvature of the surfaces 20 such that the metal adjacent said surfaces will be sprung when the bolt 18 is tightened to clamp the insulator.

15 The support may be made of iron or steel castings or in any other manner that will afford a rigid base and clamping arms having sufficient spring and resilience to operate in the manner described. For use with alternating current, however, it is desirable that at least one of the clamping members 14 shall be of non-magnetic metal, such for example as brass or bronze, and that said members shall be of skeleton construction as indicated in Fig. 2.

20 The insulator 17 may either be a split insulator as shown in the drawing or a one piece insulator depending upon the conditions of use and while the insulator support 30 described is particularly adapted to the mounting of insulators for supporting cables and large conductors extending through the insulators, I do not limit myself in using my insulator support, to insulators of this 35 type as the support may be employed with any form of insulator adapted to be held in position by the clamping action referred to.

25 In mounting the supports for use, by removing the clamping bolts, the clamping members may be removed from the bases, there being a sufficient clearance between the legs 15 to permit the toes 16 to clear the smaller portion of the apertures through the bases. The bases may thus be installed separately in proper position relatively to each other with the clamping members removed and furthermore each base may be located angularly upon its support in any position which will receive the base and permit its 50 being secured to its support to the best advantage since the aperture 11 and the recess 12 are of circular conformation thus permitting the clamping members to be turned in the bases until they line up with each other. 55 As a result the clamping members are not put in place until the cable or conductor is strung, and danger of breaking projecting parts before the electrical conductor is in place is thus eliminated.

60 The construction shown in Figs. 5 and 6 is similar to that above described, the only difference being that the base 10 is replaced by a base 22 having a semi-cylindrical conformation to engage a cylindrical support 23 such as a pipe or a rod to which the base 22

may be secured by means of a clamping plate 24 and bolts 25 as indicated, the plate 24 being preferably conformed to fit the cylindrical support 23. The base 22 has formed thereon a projecting boss 26 containing an aperture and enlarged recess the same as the aperture 11 and recess 12 above described for receiving the clamping members and permitting their operation in the same manner described in connection with Figs. 1, 2 and 3.

70 While I have shown my invention in the particular embodiments above described, I do not, however, limit myself to these exact constructions, as I may employ equivalents thereof known to the art at the time of the filing of this application without departing from the scope of the appended claims.

80 What I claim is:

1. In an insulator support, the combination of a metallic base having a circular opening therein, said opening having at its inner portion a coaxial circular recess having walls substantially at right angles to each other and substantially parallel and perpendicular respectively to the axis of said opening, two metallic clamping members each extending at one end into said opening and having at its end a toe projecting laterally and provided with surfaces fitting the right angle surfaces of said recess, each of said members having a boss adjacent said base extending towards the axis of said opening and formed outside of said boss to clamp an insulator, and devices for forcibly moving the outer ends of said members together to clamp an insulator between said members, said bosses being in firm engagement with each other and said toes firmly engaging the surfaces of said recess before said members are moved into clamping engagement with said insulator, the insulator clamping portions of said members being conformed to yield under said clamping action to firmly engage the insulator. 100

105 2. In an insulator support, the combination of a metallic base having a circular opening therein, said opening having at its inner portion a co-axial circular recess, two metallic clamping members each extending at one end into said opening and having at its end a toe projecting laterally to enter said recess, each of said members having a boss adjacent said base extending towards the axis of said opening and formed outside of said boss to hold an insulator, and devices for forcibly moving the outer ends of said members together to hold an insulator between said members, said bosses being 110 in firm engagement with each other and said toes firmly engaging the surface of said recess before said members are forced towards each other to their insulator supporting position, the insulator supporting portions of said member being conformed to yield un- 115 120 125 180

der said action to firmly engage the insulator.

3. In an insulator support, the combination of a metallic base having a circular opening therein, said opening having at its inner portion a co-axial circular recess, two metallic clamping members each extending at one end into said opening and having at its end a toe projecting laterally to enter said recess, each of said members having a boss adjacent said base extending towards the axis of said opening and formed outside of said boss to hold an insulator, and devices

for forcibly moving the outer ends of said members together to hold an insulator between said members, said bosses being in firm engagement with each other and said toes firmly engaging the surface of said recess before said members are forced towards each other to their insulator supporting position.

In witness whereof, I have hereunto subscribed my name this 3rd day of June A. D. 1919.

EDSON O. SESSIONS.
